tion of Delaware

Application November 6, 1941, Serial No. 418,009

10 Claims. (Cl. 178—29)

The present invention relates to printing telegraph apparatus and more particularly to recorders responsive to isochronous code signals having a single selective current impulse.

The principal object of the present invention is to provide an efficient page printer of simple construction operable upon the start-stop principle and comprising a minimum of operating parts.

A feature of the invention is to provide a page printing apparatus having a single selector magnet which controls a cam printing mechanism to produce a printed record in response to equal length code signals, each composed of two elements of opposite signaling characteristics whose individual time intervals are variable but complementary, so that their summation in each code signal is equal to a predetermined time constant.

In accordance with the present invention, the line signal for each character consists of a no-current starting impulse and a current definitive impulse. In the event that signal elements of opposite polarity are employed, the starting impulse will be of positive or negative current, and the definitive impulse will be of negative or positive nature, respectively. Specifically, each code signal is composed of two signal elements in which each signal element occurs but once in a code signal. The sum of the lengths of the elements in each code signal is constant, and although each element varies in length, nevertheless each element in each code signal is the complement of the other element of that particular code signal. Hence, each signal is formed and each character is determined by the relative length of the elements composing the code signal.

Upon the reception of the starting impulse, a selector magnet, which is normally energized since the idle condition of the line is of marking or current nature, releases its armature to control a power clutch, thus permitting a type wheel to rotate, in phase with a controlling element in a remote transmitter. During the rotation of the type wheel, the selector magnet, upon determination of a starting impulse which occurs simultaneously with the beginning of the definitive impulse of opposite polarity or current condition, again becomes energized and attracts and operates its armature, which action serves, in the preferred form of the invention, to actuate a cam printing mechanism to effect printing at the instant when the reversal of signaling condition occurs in the code signal cycle. In

other words, the receiving magnet, upon a reversal of signaling conditions, during the rotation of the type wheel, which occurs at the termination of the starting impulse and the beginning of the contiguous definitive impulse, attracts its armature and causes a printing hammer to operate to print a character. After printing has been effected, the type wheel is released and continues to rotate and is stopped as it completes one revolution.

A better understanding of the invention may be had from the following description taken in conjunction with the accompanying drawings, wherein like reference characters designate similar parts throughout the several views, and in which,

Fig. 1 is a graphical representation of the type of the code signal employed in operating the printer according to the present invention;

20 Fig. 2 is a perspective view of the printer, viewing the structure from one side thereof;

Fig. 3 is a perspective view of the printer, viewing it from the opposite side;

25 Fig. 4 is a side elevation of the printer showing the character selecting mechanism;

Fig. 5 is a side elevation of the printer showing the character spacing and line feeding function mechanism, and

30 Fig. 6 is a cross-sectional view of the printer showing the type wheel mechanism and the page guiding apparatus.

There is indicated in the graphical representation illustrated in Fig. 1 a sequence of monopulse isochronous code signals representative of alphabetic characters, for example, "G" and "N." All code signals according to this code are of equal length, each code signal consists of two elements of different signaling characteristics; for example, current-no current, different potential or different polarity, and each code signal comprises only a starting condition or selecting impulse A and a contiguous definitive condition or impulse B. The point at which the reversal of the current or characteristic nature of the code signal occurs is determinative of the identity of the character to be printed and is the point at which printing is effected. The stop interval between signals is indicated D in Fig. 1 and is of variable duration.

35 40 45 50 55 Having reference to Figs. 1 and 2, the printer structure comprises side plates 11 and 12 which are mounted on a base plate 13, and are maintained in a predetermined spaced relation parallel to each other by spacer rods 14, 15, and 16 (the end only of rod 16 being shown in Fig. 3).

As indicated in Figs. 2 and 3, a motor 17 is shown mounted on the side plate 11 by means of posts 18 and 19. A third post is also provided for mounting the motor 17 which post is not shown in the drawings. It is, of course, understood that the motor 17 may, if desired, be mounted on the base plate 13. It is necessary that the speed of the motor at the receiving station be regulated so that the type wheel of the printer rotates substantially in phase with a controlling element at the transmitting station.

Upon the armature shaft 20 of the motor 17 is secured a pinion gear 21 which meshes with a drive gear 22 carried on a shaft 29 suitably journaled in side plates 11 and 12. The gear 22 is connected to the shaft 29 by means of a friction clutch comprising a pair of discs of frictional material compressed between the flange of a flanged collar 23 and an indexing wheel 24. Compression is imparted to the friction clutch by a compression spring 25 positioned between the collar 23 and a nut 26 screwed onto the end of shaft 29. In this manner, the shaft 29 upon which the type wheel 27 (Fig. 3) and indexing wheel 24 are fixed is given a normal urge to rotate.

A selector magnet 31 is carried by a bracket 32 mounted on the side plate 11. An armature lever 33 is associated with magnet 31 and is carried on a pivot shaft 34 secured to the side plate 11. Armature lever 33 is provided with an arm 35 (Fig. 4) to which is pivotally connected a depending pawl member 36. Pawl 36 cooperates with a ratchet wheel or printing cam 37 and is normally urged into engagement with the cam teeth of the printing cam 37 by means of a spring 38 distended between pawl 36 and lever arm 35. The cam 37 is mounted rotatably on stud 39 fixed to the side plate 11. Upon the de-energization of magnet 31, the armature 33 will be released and will rotate slightly in a counterclockwise direction about pivot 34 under the action of a spring 41 against an eccentric stop member 42, which provides an adjustable stopping means for the armature lever 33. As the armature lever 33 is thus released, the pawl 36 is thereby raised, so as to engage the next tooth on the ratchet cam 37 so that when the armature 31 is again energized and the armature lever 33 is attracted, pawl 36 will have downward movement imparted to it which will cause the cam 37 to be stepped one angular step in the clockwise direction.

Associated with the cam 37 is a printing control lever 43 which is pivotally mounted on the side plate 11 by means of a pivot 44. The printing control lever 43 is provided with an arm 45 terminating in a V conformation whereby it cooperates with the cam teeth of the cam 37. The printing control lever 43 is also provided with a lug 46 which cooperates with the notches of the indexing wheel 24. The printing control lever 43 is provided with a spring 40 distended between lever 43 and a spring post on side plate 11 whereby arm 45 thereon is held into cooperative engagement with the cam 37.

Pivottally supported on the pivot 44 and disposed on the inside of side plate 11 is one end of the printing bail 47, the other end being correspondingly pivoted at 50 to the side plate 12 (Fig. 2). On its arm adjacent the plate 11, the printing bail 47 is provided with an eccentric stop 48 (Fig. 4) which extends through an aperture in the side plate 11 into cooperative relation with the printing control lever 43. In this manner,

when the ratchet printing cam 37 is actuated stepwise to cam out the print control lever 43 through the instrumentality of the projection 45 and the lever 43 is actuated counterclockwise against the action of its spring 40, lever 43, through the instrumentality of said eccentric stop 48, will impart corresponding rotation to the printing bail 47 against the action of its retractile spring 49 (Fig. 3) to cause the printing bail 47 to strike against the periphery of the type wheel 27 to effect the printing of a character upon the record material inserted therebetween.

The armature lever 33 (Fig. 4) is provided with an extension 51 at its free end, which cooperates with the free end of a stop-start lever 52 pivotally supported at 53 to the upper end of an orientation member 54, which is pivotally mounted at 55 on the side plate 11. Stop lever 52 is provided with a lateral portion or projection 56 which is directed toward the index wheel 24. Secured to the index wheel 24 and directed toward the side plate 11 is a projecting member 57, which cooperates with the projecting portion 56 of the stop lever 52. When the selector magnet 31 is energized, and the armature lever 33 thereof is pulled in its clockwise or attracted position against the action of its spring 41, the end 51 depresses the free end of lever 52 and urges said lever 52 in a counterclockwise direction about its pivot 53 against the action of spring 58 to bring the stop projection 56 into the path of the clockwise revolvable stop lug 57. In this manner, the shaft 29 to which the indexing wheel 24 is fixed, is held against rotation, while the gear 22 continues to rotate due to the friction clutch with which it is cooperatively related to shaft 29.

For orientation purposes the lever on index arm 54 may be rotated about its pivot 55 upon the loosening of the clamping screw 61 whereupon the stop lug 56 may be moved rightwardly or leftwardly to change the stopping position of the stop lug 57 to correspond to the reception of the start-stop code signals. Upon the de-energization of the selector magnet 31, the armature lever 33 is released and responds to its spring 41 to be rotated counterclockwise against the stop 42. As the result of this movement, the end 51 is lifted away from the free end of the stop lever 52, which is then free to respond to the pull of its spring 58 to cause said lever 52 to rotate clockwise about its pivot 53 thereby moving the stop lug 56 out of the path of the stop lug 57, thus permitting the shaft 29 to rotate.

Slidably mounted on the shaft 29 is the type wheel 27 (Fig. 3). To impart rotation to the type wheel 27, the shaft 29, between the side plates 11 and 12, is of square conformation and fits into a square hole in the type wheel 27. The type wheel 27 is moved along the shaft 29 through the instrumentality of a U-shaped bracket 63 carried slidably on an auxiliary shaft 64. Bracket 63 is provided with a vertical arm 65 (Fig. 6) which terminates in a forked end and fits into a groove integral with the hub of the type wheel 27, whereby as the bracket 63 is moved along the shaft 64, as will hereinafter appear, the type wheel 27 will be urged correspondingly along its shaft 29 by means of the articulation of the arm 65 with the hub of the type wheel. Secured to the bottom of the bracket 63 is a thin metal strip 66 which extends upwardly and is interposed between the type wheel 27 and the printing bail 47. In registry with the printing zone, the strip 66 is suitably apertured so as to permit printing to be effected there-

through and to prevent smudging of the printed record. Also pivoted on the shaft 64 is a bracket 67 which carries an inking roller 68, the bracket 67 being spring urged by a spring (not shown, but which is wound around the shaft 64) in suitable manner to bring the inking roller 68 constantly into contact with the periphery of the type wheel 27.

To accomplish the function of character spacing, a cable 71 is secured to the bracket 63 and extends around a pulley 72 (Fig. 5) carried on a bracket 73 secured to the side plate 12. The side plate 12 is apertured adjacent to pulley 72 to permit the passage of the cable 71 therethrough which is then directed from the pulley 12 to the groove in the periphery of a grooved pulley 74 which is rotatably mounted on the side plate 12 by means of a stud 75. Also mounted on stud 75 and secured to the pulley 74 by means of the screws 76 is a spacing ratchet 77. Cooperating with the ratchet 77 is a pawl 78 which is pivotally carried on the extremity of the depending arm of a bell crank lever 79 pivoted on a common stud 81 secured to the side plate 12. The horizontal arm of the bell crank 79 cooperates at its extremity with a cam 28 fixed to the shaft 29. According to the start-stop principle of operation of the printer herein described, the shaft 29 makes one revolution for each character signal, and correspondingly the cam 28 also makes one revolution to operate the bell crank 79 once for each character printed. The cam 28 is shown in Fig. 5 substantially in its stopped position wherein it can be seen that the spacing operation occurs substantially at the end of the printing cycle of operation. As the shaft 29 is released for rotation and the cam 28 thus is initiated into rotation, the cam 28 after traveling substantially 240° begins to rotate the bell crank lever 79 clockwise against the action of its spring 82 thus urging the pawl 78 leftwardly (as viewed in Fig. 5) to pick up the next or following tooth of the ratchet wheel 77. The pawl 78 is normally urged into cooperative relation with the teeth on the ratchet wheel 77 by a spring 83 distended between a projection on the pawl lever 78 and a projection on the bell crank lever 79 so that clockwise rotation is normally imparted to the pawl lever 78. After the cam 28 has rotated substantially 360°, the bell crank lever 79 is allowed to drop off the high part of the cam whereby the spring 82 effects the counterclockwise rotation of lever 79 to impart thereby rightward movement to the pawl 78 which will cause the ratchet wheel 77 to rotate a predetermined angular amount to pull cable 71 a distance sufficient to effect the character spacing of the type wheel 27, which is slidably mounted on shaft 29. The cable 71 is wound around the pulley 74 step-by-step until the type wheel 27 and its carriage has reached the end of the line; whereupon the carriage return signal is received to cause the type wheel to return, as will be presently described, to the beginning-of-line position. Of course, it is understood that the carriage return signal may be received at any time in the line so that a full winding of the cable 71 about the pulley 74 does not always occur.

To effect the carriage return operation, mechanism is provided for disengaging, and holding disengaged, the feed pawl 78 and the detent pawl 84 which is pivotally mounted on stud 85 on the side plate 12. The detent pawl 84 is normally biased into cooperation with the teeth of the

ratchet wheel 77 by a spring 86. Having reference to Fig. 2, the shaft 29 is provided at its end adjacent to the inner face of the side plate 12 with a pin 91 for controlling the carriage return operation. Pivotedly carried on pivot 92 secured to a bracket 93 fixed to the printing ball 47 is a lever 94, the lower end of which is conformed to cooperate with the pin 91 in abutting relation under certain operating conditions indicative of the carriage return function. The upper end of lever 94 has pivotal articulation with a stud 95 which extends through an aperture 96 in the side plate 12 and is fixed to the upper end of a trip lever 97 pivoted on a stud 98 affixed to the outer side of side plate 12 (Fig. 5). The lower end of lever 97 is adapted to have latching relationship with a shoulder 99 formed on a lever 101, which is pivoted on the common pivot stud 81 on which the bell crank 79 is also pivotally mounted. Lever 101 is normally biased in a counterclockwise direction by a spring 102 distended between the extremity of lever 101 and a stud 103 fixed to the side plate 12. As the carriage spacing mechanism comprising the pulley 74 operates to move the type wheel 27 from the side plate 11 to the side plate 12, a carriage return spring 104 is tensioned. One end of the carriage return spring 104 is anchored at 105 to the side plate 12, and to the other end of the carriage return spring 104 there is fastened one end of a cable 106, the other end of which is adapted to be wound around the hub 107 of a wheel-and-axle arrangement 108 rotatably mounted at 109 (Fig. 4) on the side plate 11. Secured to the sheave portion of the wheel-and-axle mechanism 108 is one end of a cable 111 (Fig. 4) which is adapted to be wound around the sheave portion of pulley 108 and which extends, as shown in Fig. 4, around a small pulley 112 positioned in an aperture 113 in the side plate 11, whereby the cable 111 passes through the side plate 11 and is attached to the U-shaped bracket 63 which carries the type wheel 27. As the type wheel mechanism is stepped along the shaft 29 from side plate 11 to side plate 12 by the character spacing mechanism through the instrumentality of pawl 78 and ratchet 77, the spring 104 is tensioned by causing the cable 111 to be unwound from the sheave portion of the wheel-and-axle mechanism 108 and the cable 106 to be wound upon the hub portion 107 thereof. With the carriage return arrangement shown, the cable 106 moves substantially one-third the distance that the cable 71 moves for each character spacing operation thus providing a very compact tensioning arrangement.

To achieve the carriage return operation, the carriage return signal is received by the selecting magnet 34 and is of such nature that, having reference to Fig. 1, the portion A of the signal (which is the portion of spacing nature) is of short duration, as is exemplified by the relative position between the pin 91 and the lower end of the lever 94 in Fig. 2. The angular position between these two elements indicates that between the initiation of rotation of shaft 29 and the instant of registry of the pin 91 with the lower end of lever 94, a short time interval has elapsed whereupon the marking portion of the code signal is impressed on the signal line to energize the magnet 34. Normally, for ordinary character printing operations, upon the energization of magnet 34 in response to the marking portion of the code signal, as shown in Fig. 1, the energization of the selector magnet 34 will cause the

operation of the armature lever 33 in a clockwise direction (as viewed in Fig. 4) to cause, through the print control lever 43, the actuation of the printing bail 47 counterclockwise (as viewed in Fig. 2), and the lever 94 is caused to rotate about the fulcrum pin 95. However, during the carriage return operation, the marking portion of the signal is received when the pin 91 is in registry or blocking relation with the lower end of the lever 94 so that when the printing bail 47 is actuated by the print control lever 43 the lower end of lever 94 abuts the pin 91 and causes the lever 94 to rotate about the pin 91 as the fulcrum thereby imparts motion to the fulcrum pin 95 which is fixed to the lever 97, and hence the lever 97 is caused to rotate about its fulcrum 98 in a counterclockwise direction (as viewed in Fig. 5) against the action of its spring 112 to cause the bottom end of the lever 97 to become disengaged from the shoulder 99 from lever 101. Lever 101 is now free to respond to the urge of its spring 102 and is thereby rotated in a counterclockwise direction. Pivotaly connected to lever 101 and depending therefrom is a pawl arm 113 which is normally biased in a counterclockwise direction by a spring 114 extending between the lever 113 and the extremity lever of 101. Lever 113 is provided on the side confronting the side plate 12 with a stud 110 which cooperates with the detent pawl 84 so that when the lever 101 is permitted, through the disengagement of the lever 97 from the shoulder 99, to respond to the pull of its string 102, this movement is imparted to the lever 113 which, through stud 110, imparts clockwise rotation to lever 84 against the action of spring 86, thereby releasing the detent pawl 84 from the ratchet wheel 77. The free end of the pawl arm 84 cooperates with an overhanging projection 115 integral with the feed pawl 78.

When the pawl 84 is raised by the stud 110, its end will cooperate with the end 115 of lever 78 to disengage the pawl 78 also from the ratchet wheel 77. The pulley 74 is now free to respond to the pull of the carriage return spring 104, which by rotating the wheel and axle arrangement 108 causes the cable 111 to be wound upon the sheave portion of the arrangement 108 while the cable 106 is unwound therefrom. In this manner the type wheel actuating bracket 63 is caused to be moved from the side plate 12 to the other side plate 11, thereby unwinding the cable 71 from the pulley 74. To maintain the pawls 78 and 84 in their disengaged position during the carriage return operation, a laterally disposed lug or projection 116 is provided on the detent pawl 84. As the ratchet wheel 77 is rotated during carriage spacing operations, a stud 117 carried thereon is also caused to move therewith so that it moves away from the lever 113 pivoted at 119 to the side plate 12 (Fig. 5). As this occurs, spring 121 causes lever 118 to be biased counterclockwise to bring its extremity to bear against the lug 116 of the detent pawl 84. Now, as the stud 117 recedes from the lever 118, and the lever 84 is raised by the stud 110, the lever 118 through its shouldered extremity acts to hold, through the projection 116, the lever 84 latched against downward movement by its spring 86. In this manner, the pawl arms 78 and 84 are held disengaged from the ratchet wheel 77 during the carriage return operation. However, at the completion of the carriage return operation, the pin or stud 117 on the ratchet wheel 77 returns to its position adjacent the lever 118 and is stopped thereat by the hook portion 122 of said lever 118.

The inside surface 123 of hook portion 122 is so contoured as to cause a budging action between the stud 117 and the lever 118 to impart a slight clockwise motion to the lever 118 against the action of spring 121 to insure the disengagement of the shouldered extremity of lever 118 from the lateral portion 116 whereupon the spacing pawl 78 is returned into engagement with the teeth of the ratchet wheel 77 by spring 83, and the detent pawl 84 is returned into engagement with the teeth of the ratchet wheel 77 by spring 86. The beginning-of-line condition of the printing mechanism is as shown in Fig. 5.

The lower end of the line feed pawl 113 is provided with a hooked portion 124 and a lateral guiding portion 125. The hooked portion 124 cooperates with a ratchet wheel 126 fixed to shaft 127 journaled in the side plates 11 and 12. The ratchet 126 is fixed to the shaft 127, and also fixed to the shaft 127 and disposed between the side plates 11 and 12 is a guide roller 128, Figs. 4 and 6. The guide portion 125 of the line feed pawl 113 cooperates with the guide member 129 (see Fig. 3) secured to the side plate 12. A jockey roller 131 is mounted on a spring 132 fastened to a bracket 133 secured to the side plate 12 whereby the line feed ratchet 126 is held or detained in its operated position. The side plates 11 and 12 are provided with bearings for a shaft 134 which carries a paper roll 135 (Figs. 3, 5, and 6) on which a paper web roll 136 is carried. Cooperating with the guide roller 128 are a pair of pressure rollers 137 located one at each extremity of the roller 128. Pressure rollers 137 are carried on suitably supported brackets 138 and are spring biased by spring 139 against the guide roller 128. The paper 136 is passed around the chute 141 and thence between the pressure rollers 137 and guide roller 128 and up along the guide 142 through the printing zone between the printing bail 47 and the spring member 66, thence out of the printing mechanism. Thus, during each carriage return operation, the line feed operation is performed simultaneously, since upon the upward motion of the pawl 113 not only are the detents 78 and 84 disengaged from the ratchet wheel 77, but also, the line feed ratchet 126 is operated by the pawl 113 to effect a line spacing or feeding operation of the paper web 136 from the roll 135.

The cam 28 not only spans the bell crank 79, but also is wide enough to act upon the lever 101 so that at the completion of the revolution of cam 28, said cam will operate upon a shoulder portion 143 of lever 101 to depress the lever 101, or rotate it clockwise against the action of its spring 102 to permit the reengagement or latching of the lever 97 with the shouldered portion 99 of lever 101, whereat the lever 101 is held until a subsequent carriage return signal is received. The shaft 127, as shown in Fig. 3, is extended beyond the side plate 12 and carries at its extremity a hand wheel 144 for manual line feeding operations.

65

General operation

Before beginning operation of the printing apparatus herein shown, the orientation index pointer 54 is manipulated so that the stop lug 56 of lever 52 is properly adjusted to effect substantial synchronization with the received signals, after which the index arm 54 is properly clamped in place. The normal operating condition of the line is a marking or current condition whereby the selector magnet 31 remains

70

75

energized, and the stop lug 56 is presented into the path of the stop lug 57 thereby holding the type wheel shaft 29 quiescent while the gear 22 constantly rotates. It is assumed that the type wheel 27 is positioned at the beginning-of-line position preparatory to printing a new line.

Due to the nature of the isochronous code signal employed in controlling the operation of the printer according to the present invention, the commencement of the start impulse causes the selector magnet 31 to be de-energized and permits spring 31 to actuate the armature lever 33 to its counterclockwise position against the stop 32, but in response to this movement of armature lever 33, stop lever 52 is removed by its spring 58 from engagement with stop lug 57, permitting the shaft 29 and the elements controlled thereby to rotate.

By this action of armature lever 33, the pawl 36 is moved into engagement with the next tooth on the printing cam 37. At an instant in the cycle of rotation of shaft 29 determined by the particular character to be printed and evidenced by a reversal of the current in the line, the magnet 31 becomes energized and instantly effects the movement or attraction of its armature lever 33, thus causing, due to the action of pawl 36 upon printing cam 37 and consequently the action of cam 37 upon print control lever 43, and in turn the action of the lever 43 upon the stud 48, the printing bail 37 to swing toward the type wheel 27 and press the page material 136 against the character selected. The projection 46 on the print control lever 43 acts on the indexing wheel 24 to arrest the type wheel momentarily from rotation. While the shaft 29 is thus rotating, the cam 28 is also operating and toward the end of the cycle of rotation, cam 28 operates upon bell crank lever 79 to rotate, through feed pawl 78, the ratchet wheel 77 to effect character spacing, in the manner previously described.

This procedure continues until the carriage return signal is received, whereupon in response to the carriage return signal the magnet 31 is first de-energized momentarily, causing the type wheel shaft 29 to rotate as previously described, and thereafter causing the selector magnet 31 to be again energized upon a reversal of current in the line at the instant when pin 91 is in registry or blocking relation with the lower end of lever 94. The energization of magnet 31 at this time causes, through lever 43, the operation of the print bail 47 and hence lever 94 to cause lever 94 to rotate clockwise about its pivot 92 to swing the latch lever 97 out of latching relation with lever 101, thereby permitting spring 102 to operate lever 101 to raise the line feed pawl 113, and through stud 110 raise the detent lever 84 and feed pawl 78 out of engagement with the character spacing ratchet 77 thereby permitting the ratchet 77 to rotate in a counterclockwise direction until the stud 117 thereon strikes against the hooked portion 122 to release or disengage the lever 118 from the portion 116 and in the meantime concurrently with the carriage return operation, the pawl 113 operates to rotate the line feed ratchet 126 clockwise (as viewed in Fig. 5) to effect the line feeding operation, after which the printing apparatus is in position for another line of printing.

What is claimed is:

1. In a telegraph page printer, a start-stop shaft, a type wheel carried thereon, means responsive to the first portion of a received signal for starting rotation of said shaft and responsive to the second portion of said signal for restoring stop conditions to said shaft, means for advancing said type wheel along said shaft to produce character spaces, and a printing bail, co-extensive with the total movement of said type wheel on said shaft, operable by said first means in response to said second portion of said received signal.
2. In a telegraph page printer, a start-stop shaft, a cam printing means, a single magnet responsive to equal length code signals, each signal comprising a start condition and a stop condition of complementary periodic lengths, means to perform character spacing, and means responsive to the start condition of a signal for initiating the rotation of said shaft and simultaneously preparing said printing means for effective operation, and subsequently responsive to the transition from start to stop condition to effect initially the camming of said printing means, secondly the operation of said character spacing means and subsequently the arrestment of said shaft.
3. In a telegraph page printer responsive to isochronous monopulse code signals comprising an initial portion and a definitive portion, a start-stop shaft, a type wheel carried thereon, a printing bail, means responsive to the initial portion of said signals to release said shaft for rotation to condition said type wheel to perform printing operations, means effective upon the transition from said initial portion to the definitive portion of said signal to operate said bail to consummate the printing operation, spacing mechanism for advancing said type wheel along said shaft to produce character spaces, and means carried by said shaft effective in response to said release of said shaft and subsequent to said printing operation to effect the operation of said spacing mechanism.
4. In a page printer, a single magnet responsive to equal length code signals, each signal comprising a first condition and a second condition of complementary periodic lengths, pawl and ratchet printing means, indexing means for said printing means, means responsive to said first condition for preparing said printing means for action, means effective upon the transition from said first to said second condition to cam said printing means to effect, under the control of said indexing means, the printing operation, means to form character spaces operative as an incident to the printing operation, and carriage return means directly controlled by said printing means.
5. In a telegraph page printer, a start-stop shaft, a cam printing means, a single magnet responsive to equal length code signals, each signal comprising a start condition and a stop condition of complementary periodic lengths, means to perform character spacing, means responsive to the start condition of a signal for initiating the rotation of said shaft and simultaneously preparing said printing means for effective operation, and subsequently responsive to the transition from start to stop condition to effect initially the camming of said printing means, secondly the operation of said character spacing means and subsequently the arrestment of said shaft, a first instrumentality associated with said printing means, a second instrumentality associated with said start-stop shaft, carriage return means, and means effective under certain predetermined operating conditions through the co-

operation of said instrumentalities to enable the operation of said carriage return means.

6. In a telegraph printer, a start-stop shaft, a cam printing means, a single magnet responsive to equal length code signals, each signal comprising a start condition and a stop condition of complementary periodic lengths, means to perform character spacing, means responsive to the start condition of a signal for initiating the rotation of said shaft and simultaneously preparing said printing means for effective operation, and subsequently responsive to the transition from start to stop condition to effect initially the camming of said printing means, secondly the operation of said character spacing means and subsequently the arrestment of said shaft, a carriage return control instrumentality, a sensing member pivotally carried by said printing means and articulated to said instrumentality, a fulcrum member associated with said start-stop shaft, and carriage return means effective under certain predetermined operating conditions through the cooperation of said sensing member and said instrumentality.

7. In a telegraph printer, a start-stop shaft, a printing means, a single magnet selecting means responsive to monopulse code signals to select a character to be printed, character spacing means, means controlled by said selecting means to effect sequentially the initiation of said shaft for rotation, the operation of said printing means, the operation of said spacing means and the arrestment of said shaft, a carriage return control instrumentality, a sensing member pivotally carried by said printing means and articulated to said instrumentality, a fulcrum member associated with said start-stop shaft, and carriage return means effective under certain predetermined operating conditions through the cooperation of said sensing member and said instrumentality.

8. In a telegraph printer, a start-stop shaft, a printing means, a single magnet selecting means responsive to monopulse code signals to select a character to be printed, character spacing means, means controlled by said selecting means to govern sequentially the initiation of said shaft for rotation, the operation of said printing means, the operation of said spacing means and the arrestment of said shaft, a carriage return control

instrumentality, a sensing member pivotally carried by said printing means and articulated to said instrumentality, a fulcrum member associated with said start-stop shaft, carriage return means effective under certain predetermined operating conditions through the cooperation of said sensing member and said instrumentality, a type wheel, means for advancing said type wheel along said shaft to produce character spaces, carriage return means, a printing bail, coextensive with the total movement of said type wheel on said shaft, operable by said first means in response to said second portion of said received signal, a first instrumentality associated with said printing means, a second instrumentality associated with said start-stop shaft, and means effective under certain predetermined operating conditions through the cooperation of said instrumentalities to enable the operation of said carriage return means.

9. In a telegraph page printer, a start-stop shaft, means responsive to the first portion of a received signal for starting rotation of said shaft and responsive to the second portion of said signal for restoring stop conditions to said shaft, a type wheel, means for advancing said type wheel along said shaft to produce character spaces, carriage return means, a printing bail, coextensive with the total movement of said type wheel on said shaft, operable by said first means in response to said second portion of said received signal, a first instrumentality associated with said printing means, a second instrumentality associated with said start-stop shaft, and means effective under certain predetermined operating conditions through the cooperation of said instrumentalities to enable the operation of said carriage return means.

10. In a telegraph page printer responsive to isochronous monopulse code signals comprising an initial portion and a definitive portion, printing means including a typing instrumentality, means responsive to the initial portion of said signals to initiate operation of said printing means, means effective upon the transition from said initial portion to the definitive portion of said signal to consummate the operation of said printing means, spacing mechanism, means to operate said spacing mechanism to effect character spacing movement of said instrumentality, and means effective in response to said initiation of operation of said printing means and subsequent to said consummation of operation of said printing means to effect the operation of said spacing mechanism operating means.

WALTER J. ZENNER.
